[57] CLAIM

The ornamented design for a handle for a fishing rod, substantially as shown and described.

DESCRIPTION

FIG. 1 is a perspective view of a handle for a fishing rod showing my new design.

FIG. 2 is a top plan view thereof.

FIG. 3 is an elevational view of one side thereof.

FIG. 4 is a bottom plan view thereof.

FIG. 5 is a rear elevational view thereof.

FIG. 6 is a front elevational view thereof.

The broken line showing of reel and rod parts is for illustrative purposes only and forms no part of the claimed design.
